DESIGN FOR A FLOWER HOLDER OR SIMILAR ARTICLE

Gunnar Madvig, Alameda, Calif.

Application July 17, 1935, Serial No. 57,701

Term of patent 3½ years

To all whom it may concern:

Be it known that I, Gunnar Madvig, a subject of the King of Denmark and a resident of the city and county of Alameda and State of California, have invented a new, original, and ornamental Design for a Flower Holder or Similar Article, of which the following is a specification, reference being had to the accompanying drawing, forming part thereof.

I claim:

The ornamental design for a flower holder or similar article substantially as shown.

GUNNAR MADVIG.
